UNITED STATES PATENT OFFICE.

CORNELIUS VANDERBILT, JR., OF NEW YORK, N. Y.

PISTOL.

1,176,003.

Specification of Letters Patent. Patented Mar. 21, 1916.

Application filed November 6, 1915. Serial No. 59,904.

To all whom it may concern:

Be it known that I, CORNELIUS VANDERBILT, Jr., a citizen of the United States, and a resident of the borough of Manhattan, 5 city and State of New York, have invented certain new and useful Improvements in Pistols, of which the following is a description.

My invention relates particularly to pistols which are small in size and which are 10 adapted to be carried conveniently and inconspicuously in the pocket of the user, for the purpose of self-protection.

One object of my invention is to provide such a pistol which shall be simple and inexpensive in construction, and, at the same 15 time, effective and reliable in operation.

Another object of my invention is to so 20 arrange the hammer-actuating trigger that practically the entire pistol may be grasped in the palm of the hand when in use, thus minimizing the effect of the recoil upon the hand and upon the position of the pistol, and insuring greater accuracy of aim.

Other objects and advantages of my im- 25 proved pistol will appear more fully from the specification and claims which follow.

In the drawing, Figure 1 is a side elevation of my improved pistol with the barrel in its operative position; Fig. 2 is a side 30 elevation of my pistol with the side plates removed and the barrel in inoperative position; Fig. 3 is a side elevation of the pistol with the side plates removed, showing the position of the various parts when the trigger has been pulled for a considerable distance, and just before the firing occurs; Fig. 35 4 is a rear elevation of the barrel portion of the pistol; Fig. 5 is a sectional view thereof, taken on the line 5—5 of Fig. 4; Fig. 6 is a transverse sectional view, taken on the line 40 6—6 of Fig. 2; Figs. 7 and 8 are side and end views, respectively, of the firing pin of the pistol; and Figs. 9 and 10 are top and side views, respectively, of a shell extractor, 45 which may be used conveniently with my pistol.

Referring to the drawing, 11 designates the stock of my pistol, and 12 designates the barrel portion thereof, the barrel portion 50 being pivotally connected to the stock, as shown at 13, and normally held in operative position with respect to the stock by a latch, such, for instance, as is illustrated at 14. As shown in Figs. 4 and 5, the barrel portion 55 comprises a plurality of barrels 15, the number here being shown as four. It is to be

understood, however, that this number may be varied without departing from my invention. Each of these barrels is adapted to receive a cartridge in its rear end, as 60 shown at 16 in Fig. 5.

The means for exploding the cartridges comprises the firing pin 17. This pin is provided with an eccentric projection 18 at the forward end, and with ratchet teeth 19 65 at the rear end. Each time the trigger is pulled the firing pin is rotated so that the projection 18 registers with a different cartridge, and the several cartridges are, therefore, exploded successively, through the operation of the trigger 20 and the hammer 21, 70 as will be more fully hereinafter described.

The trigger 20 is slidably mounted within guides 22 of the pistol stock and is adapted to move in a rectilinear direction, substantially perpendicular to the barrels when in operative position. Because of this construction, it is seen that practically the entire pistol may be grasped in the palm of the hand and the trigger pulled by a slight 80 movement of the second finger. As a result, the pistol is almost entirely concealed when in use, and also, because of the firm central grasp upon the pistol, the effect of the recoil is greatly diminished and the accuracy of 85 the aim is correspondingly improved. A spring 23 is provided for normally retaining the trigger in its lowermost position.

The hammer 21 above referred to is pivotally mounted upon the hammer pin 24 and is normally pressed toward the firing pin by the main spring 25. In order to fire the pistol then, it is merely necessary to move the hammer 21 away from the firing pin 17, to tension the spring 25, and then to free 95 the hammer 21 to the action of the spring. As a result, the hammer flies against the firing pin 17 with sufficient force to cause the firing pin to explode the cartridge. This operation of the hammer is effected from the 100 trigger by means of the spring pressed pawl 26, pivotally mounted upon the pin 27 of the trigger. The end of this pawl cooperates with the notch 28 of the hammer, and, during the greater part of the upward movement of the trigger, swings the hammer away from the firing pin, into the position shown in Fig. 3. Further movement of the trigger, however, causes the pawl to release the hammer, with the result above described. 110

The means for rotating the firing pin 17 comprises the spring pressed pawl 29, which

is also mounted upon the pin 27. During the initial upward movement of the trigger, this pawl co-operates with one of the ratchet teeth 19 of the firing pin and rotates the 5 firing pin one step before the hammer 21 is released by the pawl 26.

Any suitable means may be employed for extracting the shells from the barrels after they have been discharged. I have found it 10 convenient to make use of an extractor such as is shown at 30 in Figs. 9 and 10, which extractor may conveniently be retained between the stock frame and one of the side plates 31 when not in use. For this purpose 15 one side of the stock frame is preferably recessed, as shown at 32 in Fig. 6, for the reception of the extractor. The position of the extractor when not in use is best shown in Fig. 2.

20 The operation of my improved pistol should be apparent from the foregoing description. When it is desired to load the pistol, the latch 14 is released by pressure of the thumb, whereupon the barrel portion 25 may be moved into the position shown in Fig. 2. A cartridge is then inserted in the end of each barrel, and the barrel portion is again swung into its operative position, where it is held by the latch 14. The pistol 30 is now ready for use. After all of the cartridges have been discharged by successive operations of the trigger, the barrel portion is again moved into its inoperative position so that the shells may be extracted by 35 means of the extractor 30, and replaced with loaded cartridges, if desired.

While I have shown and described but a single form of my invention, it is to be understood that I do not wish to limit myself 40 to this precise form, since obviously many changes may be made therein without departing from the spirit of my invention.

What I claim is:

1. A pistol comprising a stock and a barrel portion, said barrel portion being provided with a plurality of barrels, each adapted to receive a cartridge, a rotary firing pin mounted in the stock adjacent the barrels and adapted to strike the cartridges 50 successively, a hammer independent of the firing pin but adapted to strike it to effect the actuation thereof, and trigger controlled means for rotating the firing pin and actuating the hammer.

55 2. A pistol comprising a stock and a barrel portion, said barrel portion being pro-

vided with a plurality of parallel barrels, each adapted to receive a cartridge, a rotary firing pin mounted in the stock adjacent the barrels and provided with an eccentric projection adapted to strike the cartridges successively as the pin is rotated; a hammer independent of the firing pin but adapted to strike it to effect the actuation thereof; and a trigger slidably mounted in the stock and 60 adapted to move in a rectilinear direction, substantially perpendicular to the barrels, to rotate the firing pin and actuate the hammer. 65

3. A pistol comprising a stock and a barrel portion, said barrel portion being provided with a plurality of parallel barrels, each adapted to receive a cartridge, a rotary firing pin mounted in the stock adjacent to the barrels and provided at one end with an eccentric projection adapted to strike the 70 cartridges successively as the pin is rotated, and at the other end a plurality of ratchet teeth, a hammer independent of the firing pin but adapted to strike it to effect the actuation thereof, a trigger, means controlled thereby for actuating the hammer, and a 75 pawl movable with the trigger and adapted to co-operate with the ratchet teeth on said firing pin to rotate said pin.

4. A pistol comprising a stock and a barrel portion, said barrel portion being provided with a plurality of parallel barrels, each adapted to receive a cartridge, a rotary firing pin mounted in the stock adjacent to the barrels and provided at one end with an eccentric projection adapted to strike the 80 cartridges successively as the pin is rotated, and at the other end with a plurality of ratchet teeth; a hammer adapted to actuate the firing pin and provided with a notch; a trigger adapted for movement in a rectilinear direction, substantially perpendicular to the barrel; a pawl connected to the trigger and adapted to co-operate with the 85 ratchet teeth on the firing pin; and a second pawl connected to the trigger and adapted to co-operate with the notch in the hammer, whereby the movement of the trigger effects the rotation of the firing pin and the actuation of the hammer. 90

In testimony whereof I have signed this specification in the presence of two subscribing witnesses.

CORNELIUS VANDERBILT, JR.
